US00D975710S

(12) **United States Design Patent** (10) **Patent No.:** **US D975,710 S**
Liao (45) **Date of Patent:** **** Jan. 17, 2023**

(54) **SET OF HANDLE FOR VR GAME
CONTROLLER AND PROTECTIVE COVER**

Primary Examiner — Austin Murphy

(71) Applicant: **Huimei Liao**, Shenzhen (CN)

(57) **CLAIM**

(72) Inventor: **Huimei Liao**, Shenzhen (CN)

The ornamental design for a set of handle for VR game controller and protective cover, as shown and described.

(**) Term: **15 Years**

(21) Appl. No.: **29/864,452**

DESCRIPTION

(22) Filed: **May 27, 2022**

FIG. 1 is a perspective view of a protective cover of a set of handle for VR game controller and protective cover showing my new design shown separately for ease of illustration;

(51) **LOC (14) Cl.** **14-02**

FIG. 2 is another perspective view thereof;

(52) **U.S. Cl.**

FIG. 3 is a front elevational view thereof;

USPC **D14/372**

FIG. 4 is a rear elevational view thereof;

(58) **Field of Classification Search**

FIG. 5 is a left side elevational view thereof;

USPC D14/372, 496, 432, 371, 125, 126, 129,

FIG. 6 is a right side elevational view thereof;

D14/299; D16/300–342; 351/158, 153,

FIG. 7 is a top plan view thereof;

351/144; 345/7–9, 905; 455/344;

FIG. 8 is a bottom plan view thereof;

348/115, 53, 121, 739

FIG. 9 is a perspective view of a handle for VR game controller of the set of handle for VR game controller and protective cover shown separately for ease of illustration;

CPC G02B 27/017; G02B 27/0158; G02B
27/0161; G02B 27/0181; G02B 27/0185;

FIG. 10 is another perspective view thereof;

G02B 27/0189

FIG. 11 is a front elevational view thereof;

See application file for complete search history.

FIG. 12 is a rear elevational view thereof;
